(57) **CLAIM**

The ornamental design for a goods delivery robot, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front perspective view of a goods delivery robot, showing our new design.

FIG. 2 is a front plan view of the goods delivery robot shown in FIG. 1.

FIG. 3 is a rear plan view of the goods delivery robot shown in FIG. 1.

FIG. 4 is a left plan view of the goods delivery robot shown in FIG. 1.

FIG. 5 is a right plan view of the goods delivery robot shown in FIG. 1; and,

FIG. 6 is a top plan view of the goods delivery robot shown in FIG. 1.

The bottom view is non-ornamental.

1 Claim, 6 Drawing Sheets
